UNITED STATES PATENT OFFICE.

JOHN MOLES, OF ERIE, PENNSYLVANIA, ASSIGNOR TO THE EUREKA COMPANY, OF
NORTH EAST, PENNSYLVANIA, A CORPORATION OF PENNSYLVANIA.

COMMUTATOR ASSEMBLING AND FINISHING DEVICE.

1,198,256.

Specification of Letters Patent. Patented Sept. 12, 1916.

Application filed July 24, 1915. Serial No. 41,692.

To all whom it may concern:

Be it known that I, JOHN MOLES, a citizen of the United States, residing at Erie, in the county of Erie and State of Pennsylvania, have invented new and useful Improvements in Commutator Assembling and Finishing Devices, of which the following is a specification.

This invention relates to commutator assembling and finishing devices and consists in certain improvements in the construction thereof as will be hereinafter fully described and pointed out in the claims.

The invention is an improvement or carrying forward of the structure shown in the patent to John Risbridger dated May 28th, 1907, #855,134.

With the device as shown in the Risbridger patent difficulty developed in assembling the device and much time was lost in getting the device in proper position on the face plate. Again in reversing the commutator in finishing it difficulty was experienced in retaining the assembled parts together.

The invention is illustrated in the accompanying drawings as follows:—

Figure 1 shows a section of the parts with the radial end of the commutator out and so held on the face plate as to finish that part of the commutator. Fig. 2 shows the same parts but with the commutator and the assembling device reversed. Fig. 3 shows a plan view of the parts as shown in Fig. 1.

1 marks the face plate and 2 the commutator bars. These commutator bars are in the usual form, having the radial end 7. Arranged around the commutator bars is a 30 contractible former 3 in the shape of a split ring, the line of separation being on a slant as clearly shown in dotted lines in Figs. 1 and 2.

5 is a compression ring of sufficient mass and rigidity to maintain its shape under pressure. The ring has a wedge or tapered opening 6 which engages the outer surface of the contractible former 3, the outer surface of the former being similarly shaped.

In practice the commutator bars are assembled, the contractible former put in place and the ring 5 forced on the former. In the final position of the ring 5, the face of the ring is flush with the face of the former so that both the former and the ring are 55 against the rear shoulder of the radial end 7.

In the first finishing of the commutator bars the ring is arranged in the face plate as shown in Fig. 1 and the shoulder formed by the radial end holds the commutator bars against endwise movement under the pressure of the tools. In this operation the radial end 7 is faced. On reversing the parts on the face plate, the radial end 7 extends into a socket 8, the socket being of sufficient diameter to more than take in the radial end 7. The socket, however, is made sufficiently shallow so that the face of the radial end will be brought into contact with the bottom 9 of the recess before the face of the ring 5 engages the face of the plate 70 so that the parts are trued by the face of the radial end on the bottom of the end.

In order to quickly center the ring 5 and consequently the commutator bars when released as well as in the preliminary cutting, 75 I provide the socket 10 in the face plate, the diameter of this socket being exactly that of the ring 5. In this manner the commutator is as nearly centered as is possible in the rough and when the ring is reversed 80 it is brought to exactly the same center so that no time whatever is lost in centering the parts. This with the fact that the parts are positioned as to face by the face of the radial end 7 which has been trued in the first operation assures centering and facing exactly 85 in harmony with the two positions of the ring. A simple clamp may be used for securing the rings on the face plate, the clamps being shown at 11 and the clamp 90 screws at 12.

What I claim as new is:—

1. In a commutator assembling and finishing device, the combination of a compression ring of sufficient mass and rigidity to 95 practically maintain its shape under ordinary use, and a contractible former adapted to engage commutator bars arranged in an annular form, said contractible former being arranged within the compression ring, the 100 former being comparatively flexible, said compression ring and former having engaging surfaces, the engaging surface of one of them having a varying diameter to compress the former by a relative movement of 105 said surfaces in engagement, the former being flexed and its shape maintained approximately a true circle as it is compressed by the compression ring, the face of the compression ring being flush with the face of 110

the contractile former when in final position.

2. In a commutator assembling and finishing device, the combination of a compression ring of sufficient mass and rigidity to practically maintain its shape under ordinary use; a contractile former adapted to engage commutator bars arranged in annular form, said contractile former being 10 comparatively flexible, said compression ring and former having engaging surfaces, the engaging surface of one of them having a varying diameter to compress the former by a relative movement of said surfaces in engagement, the former being flexed and its shape maintained approximately a true circle as it is compressed by the compression ring; a face plate having an annular concentric shoulder engaging one of the walls of the 15 compression ring; and means for securing the compression ring on the face plate.

3. In a commutator assembling and finishing device, the combination of a compression ring of sufficient mass and rigidity to practically maintain its shape under ordinary use, and a contractile former adapted to engage commutator bars arranged in annular form, said contractile former being 25 arranged within the compression ring, the former being comparatively flexible, said compression ring and former having engaging surfaces, the engaging surface of one of them having a varying diameter to compress the former by a relative movement of said surfaces in engagement, the former being flexed and its shape maintained approximately a true circle as it is compressed by the compression ring, the former being 30 of an axial thickness not greater than the compression ring whereby the compression ring may be utilized for positioning the parts.

4. In a commutator assembling and finishing device, the combination of a compression ring of sufficient mass and rigidity to practically maintain its shape under ordinary use; a contractile former adapted to 35

engage commutator bars arranged in annular form, said contractile former being arranged within the compression ring, the former being comparatively flexible, said compression ring and former having engaging surfaces, the engaging surface of one of them having a varying diameter to 40 compress the former by a relative movement of said surfaces in engagement, the former being flexed and its shape maintained approximately a true circle as it is compressed by the compression ring, the former being 45 of less axial thickness than the compression ring whereby the compression ring may be utilized for positioning the parts; and a face plate having an annular concentric shoulder engaging one of the walls of the 50 compression ring.

5. In a commutator assembling and finishing device, the combination of a compression ring of sufficient mass and rigidity to practically maintain its shape under ordinary 55 use; a contractile former adapted to engage commutator bars arranged in annular form, said contractile former being arranged within the compression ring, the former being comparatively flexible, said compression 60 ring and former having engaging surfaces, the engaging surface of one of them having a varying diameter to compress the former by a relative movement of said surfaces in engagement, the former being flexed and its 65 shape maintained approximately a true circle as it is compressed by the compression ring; a face plate having a socket of a diameter to engage the outer periphery of the compression ring to center the same, said 70 socket having its bottom faced to engage the face of the radial end of a commutator held by the former; and means for clamping the compression ring on the face plate.

In testimony whereof I have hereunto set 75 my hand in the presence of two subscribing witnesses.

JOHN MOLES.
